His Attorney.

UNITED STATES PATENT OFFICE.

ROBERT POHL, OF BERLIN, GERMANY, ASSIGNOR TO GENERAL ELECTRIC COMPANY,
A CORPORATION OF NEW YORK.

PROTECTIVE SYSTEM FOR POWER-PLANT INSTALLATIONS.

Application filed September 22, 1924, Serial No. 739,004, and in Germany November 27, 1923.

The present invention relates to protective systems for power plant installations comprising electrical generators driven by prime movers, and has for its object the provision of an improved arrangement in a protective system of the above-named type whereby in the event of overload or similar electrical disturbance on the line or source of load to which a generator is connected, the generator may be automatically and safely disconnected therefrom without affecting the operation of its prime mover, and in the event of internal short circuit or similar electrical disturbance more directly associated with the generator, its prime mover may be in addition automatically cut off from its supply of motive fluid and brought to rest.

A protective system embodying the invention is herein described, by way of example, in connection with a power plant installation comprising an alternating current generator directly connected to a steam turbine of the condensing type. This is diagrammatically illustrated in the accompanying drawing, to which for a more complete understanding of the invention, attention is now directed.

Referring to the drawing, 3 is a steam turbine having a high pressure steam inlet conduit 4 controlled by a quick-closing emergency valve 5, and an exhaust conduit 6 connected with a surface condenser 7. The exhaust conduit is provided with a normally closed atmospheric inlet valve 8 which, when opened, breaks the vacuum on the condenser and subjects the interior of the turbine and condenser to atmospheric pressure.

The valve 8 is held in the closed position against the action of a spring 9 tending to open it, by a latch member 10. At one end the latch member releasably engages the valve stem indicated at 11, which at the opposite end is pivotally mounted in a fixed supporting bracket 12. Adjacent the latch member is an electromagnet 13 which when energized attracts it in a direction to cause it to disengage the valve stem and permit the valve 8 to open under the action of spring 9. The valve arrangement shown represents any suitable arrangement providing a valve which will automatically open when released and which is capable of being electrically tripped.

The emergency valve 5 is similarly con-

trolled by an electromagnet 14, except that in this case the valve is normally held in the open position against the action of a spring 15 tending to close it. A latch member 16, holds the valve in said open position by engaging with the valve stem indicated at 17, and is pivotally mounted in a fixed support bracket 18 in such a manner that it will move in the direction of the electromagnet when the latter is energized, thereby releasing the valve stem 17 and permitting the emergency valve to close. The emergency valve may be of any suitable type which is self-closing and which is capable of being electrically tripped. The turbine may be provided with the usual throttle valve in advance of the emergency valve. However, as the throttle valve forms no part of the invention, it has been omitted for the purpose of simplifying the drawing and description.

Directly connected with the turbine by a shaft 19 is an alternating current generator indicated in outline by the dotted lines 20. Within the generator are provided alternating current windings 21, 22 and 23, and a direct current field winding or exciting field 24. The generator represents the usual revolving field type and is for this reason provided with slip rings 25 to which the field 24 is connected. The alternating current windings are by way of example, provided for three phase operation and are Y-connected to a common neutral lead 26 which is grounded as indicated at 27 through a suitable resistor 28. The output ends of the alternating current windings are connected to three-phase terminals 29 from which the output of the generator is conducted by a three-phase lead or cable 30 to a three phase line switch indicated at 31. The line switch is indicated as being in the closed position and serves to control the output of the generator, that is, to connect and disconnect the generator from its source of load which is represented by the terminal end of an outgoing three-phase line or external circuit 32 connected with the switch.

The line switch is arranged, as diagrammatically indicated, to be held in the closed position, against the action of a spring 33 tending to open it, by a catch member 34 at the end of an operating rod 35. The catch engages with the end of a plunger 36 of a solenoid magnet 37 and is released by the withdrawal of the plunger when the sole-

noid is energized. The line switch represents any suitable circuit interrupting device which automatically operates to disconnect the generator from the line when actuated by a trip device such as the solenoid 37.

Excitation for the field winding 24 of the generator 20 is supplied by a shunt-wound direct-current generator or exciter 38. This exciter is connected with the generator slip rings 25 by leads 39 in one of which leads is inserted a field rheostat 40 for controlling the current in the field 24. In circuit with the shunt field of the exciter, which is indicated at 41, is a field rheostat 42 and a fixed resistor 43, the latter being shunted by a switch 44 which is normally closed. The purpose of this resistor is to reduce the excitation of the alternating current generator 20 by lowering the voltage of the exciter 38 and hence the current in the field 24 when the switch 44 is opened. The use of this resistor will more fully appear hereinafter under the description of the operation of the system.

The switch 44 is held in the closed position by an arrangement similar to that provided for the line switch 31. This comprises a catch member 45 carried by the switch, a solenoid magnet 46 having a plunger 47 which engages with the catch, and a spring 48 which opens the switch when the solenoid is energized and the plunger is withdrawn from engagement with the catch member.

In circuit with the generator phase windings 21, 22 and 23 are the primary windings of two sets of current transformers, one set being placed between the generator windings and the neutral lead 26 as indicated at 49 and the other set being placed between the cable 30 and the line switch 31 as indicated at 50. Thus there are two transformers in each phase, one in the neutral leg adjacent the neutral lead 26, and one in the output leg adjacent the line switch 31.

The secondary windings of the two transformers in phase 21 are shown at 51 and 52. These are connected together by a series circuit 53, so that in operation a circulating current flows through them. As this represents a well known arrangement and connection of current transformers in an alternating current generator circuit, and as all of the transformers are of the same electrical rating, the secondaries and duplicate connections for the remaining transformers have been omitted with the intention of simplifying the drawing and rendering the invention more easily understood.

At points of equal potential 54 along the circuit 53, the actuating coil 55 of a relay 56 is connected in parallel with both secondaries 51 and 52. Adjacent the secondary 52, the actuating coil 57 of a second relay 58 is connected into the circuit 53 in series with the

secondaries 51 and 52. By this arrangement the actuating coil 57 of relay 58 is subjected to the circulating current which flows through the secondaries 51 and 52 when load current flows through their respective primary windings, and is arranged to cause a pair of normally open contacts 59 and 60 to close when this circulating current reaches a predetermined high value, corresponding for example to an overload on the line 32, while the actuating coil 55 of relay 56 is energized only when a differential current flows through it from the secondaries 51 and 52 as a result of a condition of operation setting up a difference between the current flowing through the generator winding 21 and the line connected with it. Such a condition of operation is represented, for example, by an internal short circuit or ground at some point within the generator or cable 30, that is, between the current transformers 49 and 50, accompanying a breakdown of the insulation, when a greater current will flow through the primary associated with the secondary 51 than will flow through the primary associated with the secondary 52. The coil 55 is arranged to close a pair of normally open contacts 61 and 62 when the differential current reaches a predetermined low value.

In brief the arrangement above described is such that relay 58 operates when an external electrical disturbance develops at any point beyond the current transformer 50 in the direction of the line 32, such as a predetermined overload, ground or short circuit on said line while relay 56 operates when an internal electrical disturbance occurs. The term "internal electrical disturbance", as used herein is intended to include any disturbance in the nature of a ground or short circuit which may develop in the generator windings, its connecting cable 30, or either set of transformers 49 and 50, and is used to distinguish such disturbances from external electrical disturbances mentioned above.

The secondaries and connections for the transformers in phases 22 and 23 of the generator, which have been omitted for reasons hereinbefore pointed out, may be considered to be the same as shown in connection with 21 and to be provided with overload and differentially operated relays having contacts which are connected in parallel with those of relays 58 and 56 respectively.

The electromagnets 13 and 14 and the solenoid magnets 37 and 46 are energized from supply mains indicated at 63 and 64 through circuits controlled by the contacts of the relays 56 and 58. The supply mains 63 and 64 should preferably be maintained at a constant voltage and should provide substantially unfailing energy. This may be accomplished, by connecting them with a

source of constant potential energy, such as for example, a storage battery (not shown).

Electromagnets 13 and 14 connected in parallel to a circuit 65, one side of which is connected to the upper contact 61 of relay 56 and the other side of which is connected to one side 63 of the supply mains 63, 64. The solenoid magnets 37 and 46 are connected in parallel to a similar circuit 66, one side of which is connected to the lower contact 62 of relay 56 and to the upper contact 59 of relay 58, while the other side is connected to supply main 64. The remaining contact 60 of relay 58 is connected by a lead 15 67 to the supply main 63.

The above arrangement is such that when the contacts 59 and 60 of relay 58 are closed, a circuit is closed from supply main 63 through the lead 67 and contacts 60 and 59, 20 through solenoids 37 and 46 in parallel by way of one side of circuit 66, and back through the opposite side of circuit 66 to the supply main 64, thus causing the solenoids 37 and 46 to be energized by placing them in parallel across the supply mains 63 and 64. When the contacts 61 and 62 of relay 56 are closed, a circuit is closed from the supply main 63 through one side of circuit 65, through both electromagnets 13 and 14 in parallel, back through the opposite side of circuit 65, through the contacts 61 and 62 to one side of circuit 66, through both solenoids 37 and 46 in parallel and back through the opposite side of circuit 66 to the supply main 64, thus causing the solenoids 37 and 46 and electromagnets 13 and 14 to be energized by placing the paralleled solenoids in series with the paralleled electromagnets across the supply mains 63 and 64. The solenoids and electromagnets are designed so that the reduction in current caused by placing them in the above series relation does not affect their proper operation.

The operation of the system is as follows: 45 With the generator in operation and delivering power to line 32, main switch 31 is closed, the exciter field resistor 43 is short circuited by the closed switch 44, emergency valve 5 is open and atmospheric relief 8 is closed, said switches and valves being latched in their respective operating positions, all as indicated in the drawing.

When overload on the line 32 or similar 55 external electrical disturbance develops, the relay 58 is operated to close contacts 59 and 60 by a corresponding overload current flowing through the secondaries 51 and 52. The solenoids 37 and 46 are then energized and the main switch 31 and switch are tripped open. As the overload is thus suddenly taken off the generator by the opening of the main switch 31, the voltage delivered by it may rise to a high value, that is, to a value sufficiently high to dangerously stress the insulation. This condition is prevented in

the arrangement shown by the simultaneous opening of the switch 44, which, as hereinbefore explained, reduces its excitation and consequently effects a lowering of its output voltage.

The normal operation is restored by reclosing switch 44 after adjusting the exciter field rheostat 42 so that this will not raise the generator output voltage above a permissible high value and then reclosing the main switch 31 after finally adjusting the generator output voltage to the proper value by either the exciter field rheostat 42 or the generator field rheostat 40.

If internal electrical disturbances develop, that is, disturbances in the nature of a short circuit or ground at any point between transformers 49 and 50, or even within transformers 50, the resulting ground or short circuit current flow will not pass through transformers 50, but only through transformers 49; hence an unbalance between the output of secondaries 51 and 52 will be set up and the relay 56 will operate to close contacts 61 and 62, thus energizing the magnets 13 and 14 as well as the solenoids 37 and 46. This effects the opening of switches 31 and 44 as before explained and in addition it effects the tripping of the valves 5 and 8, emergency valve 5 closing and atmospheric inlet valve 8 opening. Thus upon the development of internal electrical disturbances sufficient to operate relay 56, the generator is cut off from the line and its voltage reduced by the opening of switches 31 and 44 as in the case of external electrical disturbances. In addition the turbine is cut off from its supply by the closing of emergency valve 5 whereby it will come to rest, and atmospheric pressure is admitted to the interior of the turbine and condenser by the opening of atmospheric inlet valve 8, whereby a braking load will be applied to the moving parts of the turbine through increased windage resistance, to bring the turbine to rest more rapidly.

The protective system provided, thus operates to cut off the generator from the line upon the occurrence of either an internal or an external electrical disturbance. Since the external disturbances are ordinarily temporary in nature, the system provides that the turbine or prime mover is kept in operation during their occurrence but in the case of internal disturbances which are usually accompanied by damage requiring attention and repairs, the system further provides for stopping the prime mover, the stopping preferably being hastened by admitting atmospheric pressure to the interior of the prime mover.

The lowering of the generator excitation is especially desirable under internal short circuit conditions as it serves to lower the short circuit current which may be set up

thereby, and, in case the internal electrical disturbance results in fire within the generator, the rapid stopping of the generator is especially desirable, this being provided in the present example, by the admission of atmospheric pressure to the prime mover, as above mentioned.

The ground resistor 28 is provided in the neutral, grounded lead 26 to limit to a certain low value the current which may flow as a result of a grounded phase, either external or internal. The resistor is, however, such that sufficient current will be passed by it to cause the relay 58 to operate if the ground is in the nature of an overload on the line, and to cause relay 56 to operate if the ground is internal, that is, within the cable 30, the generator windings or the current transformers 49 and 50.

In accordance with the provisions of the patent statutes, I have described the principle of operation of my invention, together with the apparatus which I consider to represent the best embodiment thereof, but I desire to have it understood that the apparatus shown is only illustrative, and that the invention may be carried out by other means.

What I claim as new and desire to secure by Letters Patent of the United States, is,—

1. The combination with a prime mover and an electrical generator connected therewith, of an external electrical circuit connected with the generator, means for disconnecting the generator from said circuit, means responsive to external electrical disturbances for operating said disconnecting means, and means responsive to internal electrical disturbances for operating said disconnecting means and stopping the prime mover, said second and third named means including in common a current transformer connected with the generator, and a current transformer connected between the generator and the external circuit, said transformers having secondaries connected to form a series circuit, said second-named means including a current-responsive device in said series circuit, and said third-named means including a current-responsive device connected across normally neutral points of said series circuit.

2. The combination with a prime mover having a motive fluid supply and an electrical generator connected with the prime mover, of an external electrical circuit connected with the generator, means for disconnecting the generator from said circuit, means responsive to external electrical disturbances for operating said disconnecting means, and means responsive to internal electrical disturbances for operating said disconnecting means, cutting off the motive fluid supply from the prime mover and applying a braking load to stop said prime mover and con-

nected generator, said means including in common a current transformer connected with the generator, and a current transformer connected between the generator and the external circuit, said transformers having secondaries connected to form a series circuit, said first-named means including a current-responsive device in said series circuit, and said second-named means including a current-responsive device connected across normally neutral points of said series circuit.

3. The combination with a prime mover and an electrical generator connected therewith having an exciting field, of a source of electrical load connected with the generator, a switch in said connection, means responsive to overload on the generator for simultaneously opening said switch and reducing the excitation of the generator field, and means responsive to internal electrical disturbances associated with the generator for simultaneously opening the switch, reducing the excitation of the generator field and stopping the prime mover, said means having in common a control circuit connected with the generator and a controlled circuit, a portion of which last-named circuit is controlled by said first-named means and all of which last-named circuit is controlled by said second-named means.

4. In combination, an elastic fluid prime mover having an elastic fluid inlet and an emergency rapid-closing valve controlling said inlet, an electrical generator connected with said prime mover, an exciting field for the generator, a source of load to which the generator is connected, a switch in said connection, relay-controlled means responsive to overload on the generator for simultaneously opening said switch and reducing the excitation of the generator field, and relay-controlled means responsive to internal electrical disturbances associated with the generator for simultaneously opening said switch, reducing the excitation of the generator field and permitting the emergency valve to close, said means having in common a control circuit connected with the generator and a controlled circuit, a portion of which last-named circuit is controlled by said first-named means and all of which last-named circuit is controlled by said second-named means.

5. In combination, an elastic fluid prime mover having an elastic fluid inlet and an exhaust outlet, a condenser connected with said exhaust outlet, a normally closed atmospheric inlet valve for the prime mover adjacent the exhaust outlet, said valve being releasable to automatically open, a normally open emergency rapid-closing valve controlling the elastic fluid inlet, said valve being releasable to automatically close, an electrical generator connected with the prime

5 mover, an exciting field for the generator, a source of load to which the generator is connected, a switch in said connection, relay-controlled means responsive to overload on the generator for simultaneously opening said switch and reducing the excitation of the generator field, and relay-controlled means responsive to internal electrical disturbances associated with the generator for 10 simultaneously opening the switch, reducing the excitation of the generator field and releasing the emergency and atmospheric inlet valves, said means having in common a control circuit connected with the generator 15 and a controlled circuit, a portion of which last-named circuit is controlled by said first-named means and all of which circuit is controlled by said second-named means.

6. The combination with a prime mover

and an electrical generator connected there- 20 with having an alternating current winding, of an external electrical circuit connected with said winding, a switch in said connection, current transformers in circuit with the generator winding on each side thereof, 25 said transformers having secondaries connected to form a series circuit, a relay having an operating coil connected in said series circuit, a second relay having an operating coil connected with normally neutral 30 points in said series circuit, means controlled by said relays for disconnecting the generator winding from the external circuit, and means controlled by the second-named 35 relay for stopping the prime mover.

In witness whereof, I have hereunto set my hand this 27 day of August, 1924.

ROBERT POHL.
